United States Patent Office

Des. 225,597

Patented Dec. 26, 1972

225,597

CHAIR

Stanley H. Hutchinson, Sierra Madre, Calif., assignor to David E. Vaughn, Owosso, Mich.

Filed Mar. 22, 1971, Ser. No. 127,061

Term of patent 14 years

Int. Cl. D6—02

U.S. Cl. D6—20

FIG. 1 is a front perspective view of a chair showing my new design;

FIG. 2 is a rear perspective view of the chair;

FIG. 3 is a front elevational view of the chair;

FIG. 4 is a top plan view of the chair;

FIG. 5 is a side elevational view of the chair; and

FIG. 6 is a rear elevational view of the chair.

I claim:

The ornamental design for a chair, as shown.
